METHOD OF FORMING SPOOLS

Frederick J. Bieber and Lyle E. Overholt, Minneapolis, Minn., assignors to Acrometal Products, Inc., Minneapolis, Minn., a corporation of Minnesota

Application March 19, 1952, Serial No. 277,512

3 Claims. (Cl. 29—148)

1

Our invention relates to a method of forming winding spools, bobbins or drums for winding of textile threads, wire or the like.

The primary object of our invention is the provision of a novel method of forming a winding drum of the class above-described, which will produce at relatively low cost an extremely rugged and strong winding spool or bobbin which may be successfully reused a great number of times.

A still further object of our invention is the provision of a novel method of producing spools which are light in weight and yet have great rigidity and strength.

A still further object of our invention is the provision of the novel method of forming and assembling the drum-forming element and the flanges which project radially outwardly from the opposite ends thereof.

The above and still further objects of our invention will become apparent from the following detailed specification, appended claims, and attached drawings.

Referring to the drawings, wherein like characters indicate like parts throughout the several views:

Fig. 1 is a view partly in side elevation and partly in axial section, some parts being broken away, said view illustrating one stage in our novel method;

Fig. 2 is an enlarged fragmentary view partly in side elevation and partly in axial section, illustrating a further step in our novel method;

Fig. 3 is a fragmentary view corresponding to Fig. 2 but illustrating a still further step in our novel method;

Fig. 4 is a view corresponding to Fig. 1, but illustrating a still further step in our novel method;

Fig. 5 is a view as seen from the line 5—5 of Fig. 6 and illustrating a still further step in our novel method;

Fig. 6 is a view as seen from the line 6—6 of Fig. 5;

Fig. 7 is a transverse section taken on the line 7—7 of Fig. 5;

Fig. 8 is a transverse section taken on the line 8—8 of Fig. 5; and

Fig. 9 is a view in transverse section of a modified form of bearing assembly.

Referring with greater particularity to the

drawings, the numeral 1 indicates an elongated tubular drum-forming element, preferably formed of aluminum or the like and having sufficient thickness to enable same to withstand considerable external pressure without bending or warping. In closely spaced relation to the opposite ends of the drum-forming element 1, endless circumferential channels 2 are formed. As shown, the channels 2 preferably have bottoms 3 which are at right angles to the side walls 4 thereof. Channels 2 may be formed either in a lathe, screw machine, or the like.

The next step in our novel method is to counterbore the opposite ends of the drum-forming element 1 to provide shoulders 5 axially inwardly-spaced from the channels 2. Thereafter, the opposite ends of the drum-forming element 1 are placed into an annular die 6, the tapered walls 7 of which cause said ends to be uniformly diametrically reduced in diameter, as shown in Fig. 2. Thereafter, we provide annular flange-forming elements 8 with central openings 9 which have maximum diameters corresponding approximately to the external diameter of said drum-forming element 1, and central endless circumferentially-extended ribs 10 which have diameters and shapes corresponding to the channels 2.

It will be noted, by reference to Fig. 3, that the opposite ends of the tubular drum-forming element 1, axially outwardly of the inner side walls 4 of the channels 2, have been reduced only sufficiently to permit the ribs 10 of the flange-forming elements 8 to come into contact with said inner side walls 4 of the channels 2. Thereafter, as illustrated in Fig. 4, an expander die 11 is caused to be inserted into the contracted opposite ends of the drum-forming element 1, whereby to expand said contracted ends back to their original diameters and lock the ribs 10 within the channels 2. Preferably and as shown, the flanges 8 are provided with rims 12 formed from nylon or other suitable material.

As a further step in my novel process, we provide a pair of tubular bearing members identified in their entirety by the numerals 13 and 14 and each including a reduced end 15 and an enlarged head 16. The heads 16 include annular spacing elements or bushings 17 snugly receivable within the counterbored outer ends of the drum-form-

ing element 1. End portions 18 are preferably formed integrally with the reduced end portions 13 and keyed to the bushings 17 as at 19 to prevent rotation of one with respect to the other thereof. It will be observed that the overall axial length of each of the bearing members 13 and 14 is considerably less than half the length of the drum-forming element 1.

A sleeve 19, formed of sheet metal or the like and preferably having its opposite ends back-turned upon itself as at 20 for the purpose of reinforcement, is next inserted into the drum-forming element 1 and the bearing assemblies 13 and 14 are inserted into opposite ends thereof, whereby to cause the reduced ends 15 to be telescopically received in opposite ends of the sleeve 19 and the bushings 17 to be received within the counterbored opposite ends of the drum-forming element 1 in contact with the shoulders 5 thereof. Retainer plates 21 are then inserted into the counterbored ends of the drum-forming element 1 in contact with the heads 16, particularly portions 17 and 18 thereof. Finally, the opposite ends of the drum-forming element 1 are peaned over the retainer plates 21 at circumferentially-spaced points as indicated by the numeral 22 (see particularly Figs. 5 and 6).

It will be noted that the reduced end 15 of bearing 13 is provided with tapering walls 23 for the reception of a tapered spindle, whereas retainer plate 21 and end portion 18 of said bearing 13 are provided with aligned keyways 24 and 25 respectively for the reception of a keyed spindle.

In Fig. 9, we have illustrated a modified form of bearing assembly, identified in its entirety by the numeral 26 and including a tubular reduced axially inwardly-projecting portion 27 having an integrally-formed radially outwardly-projecting head 28. The bearing portion 27 is formed preferably from nylon or the like. The head 28 is provided with a radially-projecting flange 29. An annular mounting plate 30 receives the head 28 axially inwardly of the flange 29; whereas a cooperating mounting plate 31 having an annular notch 32 therein for the reception of the flange 29 is positioned axially outwardly thereof. As shown, the head 28 is provided with a toothed portion 33 receivable within a notch 34 in the mounting plate 30. Rotation of the bearing 27 with respect to the mounting members is prevented in this manner. On their peripheral edges, the mounting plates 30 and 31 are provided with aligned slots 35 and 36 respectively into which fingers 37, formed integrally with retainer or facing plates 38 are positioned. It will be noted that the extreme inner ends of the fingers 37 are bent axially inwardly over the mounting plate 30, so as to lock all the elements together. This structure has the advantage of being able to be assembled as a unit and thereafter placed in position in the counterbored opposite ends of the drum-forming element 1 and finally locked in place therein by peaning or the like, as indicated by the numeral 32 of Fig. 5.

While we have disclosed and claimed a novel spool and method of forming same, it should be obvious that the same is capable of modification without departure from the spirit and scope of the invention as defined in the appended claims.

What we claim is:

1. The method of forming a spool which comprises forming circumferentially-extended channels in the outer surface of a cylindrical drum-forming element in closely spaced relation to the

opposite ends thereof, counterboring said opposite ends of said drum-forming element whereby to form annular shoulders axially inwardly spaced from said channels, providing flange-forming elements with central openings having maximum diameters corresponding to the external diameter of said drum-forming element and central radially inwardly-projecting circumferentially-extended ribs corresponding in width and depth to the channels in said drum-forming element, deforming the opposite ends of said drum-forming element whereby to uniformly reduce the diameters thereof axially outwardly of the inner walls of said channels to diameters slightly less than the diameters of said ribs, placing said flange-forming elements over said reduced ends with the ribs thereof in engagement with the inner walls of said channels, thereafter expanding said opposite outer ends to their normal diameters to lock said ribs in said channels, forming a pair of annular bearing members having enlarged heads capable of being snugly received within the counterbored opposite ends of said drum-forming element and reduced inner end portions, the overall axial length of said bearing members being considerably less than half the length of said drum-forming element, placing within said drum-forming element a tubular sleeve having an internal diameter approximating that of the external diameter of the reduced portions of said bearing members, inserting said bearing members into the opposite ends of said drum-forming element whereby to cause the reduced end portions thereof to be telescopically received within said sleeve and to cause the enlarged heads to be received within said counterbored portions in engagement with the shoulders thereof, and thereafter creating locking engagement between said bearing members and said drum-forming element.

2. The method defined in claim 1 in which said locking engagement is caused by peaning the opposite ends of said drum-forming element over the adjacent heads of said bearing members.

3. The method of forming a spool which comprises forming circumferentially-extended channels in the outer surface of a cylindrical drum-forming element in closely spaced relation to the opposite ends thereof, counterboring said opposite ends of said drum-forming elements whereby to form annular shoulders axially inwardly spaced from said channels, providing flange-forming elements with central openings having maximum diameters corresponding to the external diameter of said drum-forming element and central radially inwardly-projecting circumferentially-extended ribs corresponding in width and depth to the channels in said drum-forming element, deforming the opposite ends of said drum-forming element whereby to uniformly reduce the diameters thereof axially outwardly of the inner walls of said channels to diameters slightly less than the diameters of said ribs, placing said flange-forming elements over said reduced ends with the ribs thereof in engagement with the inner walls of said channels, thereafter expanding said opposite outer ends to their normal diameters to lock said ribs in said channels, forming a pair of annular bearing members having enlarged heads capable of being snugly received within the counterbored opposite ends of said drum-forming element and reduced inner end portions, placing within said drum-forming element a tubular sleeve having an internal diameter approximating that of the external diam-

eter of the reduced portions of said bearing members, inserting said bearing members into the opposite ends of said drum-forming element whereby to cause the reduced end portions thereof to be telescopically received within said sleeve and to cause the enlarged heads to be received within said counterbored portions in engagement with the shoulders thereof, and thereafter creating locking engagement between said bearing members and said drum-forming element.

FREDERICK J. BIEBER.
LYLE E. OVERHOLT.
